UNITED STATES PATENT OFFICE.

FRANK BATEMAN, OF GRENLLOCH, NEW JERSEY, ASSIGNOR TO THE BATEMAN MANUFACTURING COMPANY, OF SAME PLACE.

DESIGN FOR A FRAME FOR CULTIVATORS.

SPECIFICATION forming part of Design No. 27,013, dated May 4, 1897.

Application filed October 21, 1896. Serial No. 609,618. Term of patent 7 years.

To all whom it may concern:

Be it known that I, FRANK BATEMAN, a citizen of the United States, and a resident of Grenloch, Camden county, New Jersey, have 5 invented a new and original Design for a Frame for Cultivators, of which the following is a specification.

My design for a frame for a cultivator is fully shown in the accompanying drawing, 10 which represents a perspective view of said frame.

The frame comprises a vertical arch A, upon each of the legs of which is a T-shaped pro-

jection B, and extending forwardly from each of these projections is a bar D. 15

I claim as my invention—

The design for a frame for a cultivator, substantially as shown and described.

In testimony whereof I have signed my name to this specification in the presence of 20 two subscribing witnesses.

FRANK BATEMAN.
